BLOWER

Willard Langdon Morrison, Lake Forest, Ill.

Application August 3, 1931, Serial No. 554,752
Renewed August 30, 1937

7 Claims. (Cl. 230—130)

This invention relates to blowers and has for its object to provide a new and improved device of this description.

The invention is particularly adapted to be used as a multi-stage blower, that is a blower having more than one wheel. With multi-stage blowers as heretofore made, there has been very great difficulty due to leakage back through the housing and wheel, and due to the further fact that there is a great loss in the passage from one wheel to the other. One of the objects of the present invention is to provide a device which will prevent this leakage and this loss, and which may be efficiently used as a multi-stage blower.

The invention has other objects which are more particularly pointed out in the accompanying description.

Referring now to the drawing,

Fig. 1 is a sectional view through one form of blower embodying the invention;

Fig. 2 is an end view of the blower shown in Fig. 1, with parts broken away.

Like numerals refer to like parts throughout the several figures.

Referring now to the drawing, I have shown a construction wherein each blower is provided with a housing consisting of the members 1 and 2. When more than one blower is used, the housings for the different wheels are connected together. The housing of the blower is rotated. For this purpose the member 1 of the housing, at one end, is provided with the elongated portion 3 which is mounted in suitable bearings. As herein shown, it is mounted in bearings on a support 4 and I prefer to provide ball bearings 5 for this purpose. At the other end of the device the section 2 of the housing is provided with the elongated portion 6 which is rotatably mounted in a bearing, which is shown as a ball bearing 7, in the support 8.

Each housing is provided with a series of pusher blades 9, these pusher blades, in the particular construction shown, being connected with the sections 1 of each housing. The rotation of the housing causes these pusher blades to force the air forward. The section 2 of one housing is connected to the section 1 of the adjacent housing by a passageway 10. The pusher blades 9 are connected to a central hub 11 and extend outwardly from said hub, as clearly shown in Fig. 2.

A shaft 12 is mounted in the hubs 11 of the pusher blades and has connected therewith the vanes 13, which are located in proximity to the pusher blades 9 and which have the curved ends

14, as shown. These vanes are connected to the shaft 12 by means of a central hub 15 thereon, the central hub being fastened to the shaft so that the vanes do not rotate with relation to the shaft. The shaft 12 is preferably provided with ball bearings 17 in the hub of the pusher blades. The shaft 12 is held against rotation, thereby holding the vanes 13 against rotation, while the pusher blades 9 rotate with the casing.

Any suitable means may be provided for preventing the shaft 12 from rotating. As herein shown, this is accomplished by means of a fixed member 18 which is attached by a fastening member 19 to the stationary bearing support 8. This fixed member projects between two of the vanes 13, as shown in Fig. 1, and may be attached to one of these vanes if desired. It will thus be seen that this fixed member holds the shaft 12 and the vanes 13 from rotating.

The admission opening 20, it will be noted, is 20 in alignment with the discharge opening 10 from the first wheel to the second wheel, and these two openings are in alignment with all of the discharge openings regardless of the number of wheels that are used. The pusher blades 9 25 deliver the air in a generally axial direction, with relation to the casing, to the vanes 13 and these vanes 13 deliver air in a generally axial direction, with relation to the casing, through the discharge opening 10 and to the pusher blades 9 of the next 30 wheel. It will thus be seen that the air is moving in a generally axial direction through all of the casing, and without abrupt turns.

The pusher blades 9 are so designed as to give 35 directional delivery to the air, there being no plenum chamber to be filled, the pusher blades directly driving the air to the vanes 13 and the vanes 13 guiding and directing the air forward into the next wheel where it is taken up again by the pusher blades of the next wheel and directed to the vanes 13, and is then directed out through the discharge 16. It will thus be seen that the air is directly forced from one wheel to the other and is not required to turn abrupt corners. It will further be seen that there are no collection chambers required, but only directional chambers which displace the plenum chamber, these directional chambers being equipped with vanes to intercept the air that is directionally impelled toward them. This makes 40 it unnecessary to have any plenum chamber or reservoir. It will further be seen that the entire production of the first wheel, that is one-hundred percent of the air moved thereby, goes to the second one and this will be continued for as 45 50 55

many wheels as required, whereas the usual blower is only able to send forward about sixty percent of the air acted upon.

It will thus be seen that this multi-stage blower utilizes a new principle which consists in directly delivering all of the air from the pusher blades of one wheel into the discharge, and when more than one wheel is used, into the adjacent wheel, the pressure being increased proportionately from wheel to wheel. It will further be seen that by means of this device the pressure can be increased from one wheel to the other proportionate to the power utilized in driving the wheel, and without undue loss. It will further be seen that by means of this construction very high pressure can be attained with wheels of comparatively small diameter. It will be seen that by using small wheels and providing a large number of them in tandem, a high pressure can be provided by a machine which occupies only a comparatively small space.

It will further be seen that this device has a venturi action. The air, for example, passes from the first unit through the discharge 10, which is comparatively small, and then expands into the second unit, and this is continued through the different wheels and stages so that the ultimate discharge is smaller in cross section than the cross section of the admission opening.

30 In this device the air is moved forward in a streamline flow, and hence this blower might be termed a streamline blower, very greatly minimizing the resistance to the flow of the air.

In view of this flow of the air through the casings, whereby the absence of abrupt changes in direction is secured, the noise, when the blower is actuated, is very greatly reduced.

It will be noted that the outer connecting walls of the adjacent casings project inwardly towards the center axis of the casings to form a constricted passageway between the adjacent casings. It will further be noted that the air in the blower is at all times passing along the external revolving walls of the casings and being cooled throughout its entire course through the blower. This blower compresses the air and when it compresses it the temperature is raised. Since this air passes along the outside walls of the various sections or blowers and is at a temperature higher than the outside air, a portion of this heat due to the revolving of the casings is removed. The removal of the heat from the air is due to the fact that the movement of the casing changes at a comparatively rapid rate the air which is in contact with the outside surface of the casing so as to continuously apply cool air to the outside surface of the casing and continuously remove the warm air from the surface of the casing, and move such warm air away from the casing. When the air is then discharged from the blower and again expands to its normal volume, this volume will have less heat than when it entered the blower and hence can be used to cool a compartment. The amount of cooling can be regulated by the number of blowers arranged in tandem and the speed of these blowers.

I claim:

1. A centrifugal air blower comprising a casing, having centrally located admission and discharge openings smaller in cross sectional area than the casing, a series of pusher blades connected with the casing, and projecting laterally beyond the periphery of the admission and discharge openings, means for rotating the casing

so as to rotate said blades, and a series of vanes in proximity to said pusher blades and projecting laterally beyond the periphery of the admission and discharge openings and to the outer ends of which the air is delivered from the pusher blades, the vanes held against rotation, the outer ends of the vanes projecting beyond the outer ends of the pusher blades so that air is received by said ends from said pusher blades while the air is moving in a generally radial direction, the air at all points of its flow moving in a forward direction.

2. A centrifugal air blower comprising a casing, having centrally located admission and discharge openings smaller in cross sectional area than the casing, a series of pusher blades connected with the casing, and projecting laterally beyond the periphery of the admission and discharge openings, means for rotating the casing so as to rotate said blades, and a series of vanes in proximity to said pusher blades and projecting laterally beyond the periphery of the admission and discharge openings and to the outer ends of which the air is delivered from the pusher blades, a non-rotating shaft with which said pusher blades are rotatably connected, said vanes being connected with said shaft so as to be held against rotation thereby, the outer ends of the vanes projecting beyond the outer ends of the pusher blades, the adjacent cooperating vanes and pusher blades having portions in the same radial plane, the air at all points of its flow moving in a forward direction.

3. A centrifugal air blower comprising a plurality of casings each having a centrally located admission and discharge opening smaller in cross sectional area than the casings, said casings being connected together, the discharge opening of one casing communicating with the admission opening of the adjacent casing, a series of pusher blades connected with each casing, means for simultaneously rotating all of said casings, a series of non-rotating vanes in each of said casings, the pusher blades and vanes projecting laterally beyond the periphery of the admission and discharge openings, the pusher blades in each casing delivering air to the vanes in each casing, and the vanes of one casing delivering air to the pusher blades of the adjacent casing, the outer ends of the vanes projecting beyond the outer ends of the pusher blades, the adjacent cooperating vanes and pusher blades having portions in the same radial plane, the air at all points of its flow moving in a forward direction.

4. A centrifugal air blower comprising a plurality of casings each having a centrally located admission and discharge opening smaller in cross sectional area than the casings, said casings being connected together, the discharge opening of one casing communicating with the admission opening of the adjacent casing, a series of pusher blades connected with each casing, means for simultaneously rotating all of said casings, a series of non-rotating vanes in each of said casings, the pusher blades and vanes projecting laterally beyond the periphery of the admission and discharge openings, the pusher blades in each casing delivering air to the vanes in each casing, and the vanes of one casing delivering air to the pusher blades of the adjacent casing, a non-rotating shaft extending through said casings and upon which said vanes are mounted, the outer ends of the vanes projecting beyond the outer ends of the pusher blades, the adjacent cooperating vanes and pusher blades

having portions in the same radial plane, the air at all points of its flow moving in a forward direction.

5. A centrifugal air blower comprising a plurality of casings, each having a centrally located admission and discharge opening smaller in cross sectional area than the casings, said casings being connected together, the discharge opening of one casing communicating with the admission opening of the adjacent casing, a series of pusher blades connected with each casing, means for simultaneously rotating all of said casing, a series of non-rotating vanes in each of said casings, the pusher blades and vanes projecting laterally beyond the periphery of the admission and discharge openings, the pusher blades in each casing delivering air to the vanes in each casing, and the vanes of one casing delivering air to the pusher blades of the adjacent casing, a shaft supported by said pusher blades, the vanes being rigidly attached to said shaft, and means for holding said shaft against rotation when the casings are rotated, the air at all points of its flow moving in a forward direction.
25. 6. A centrifugal air blower comprising a plurality of revolving casings connected together and having their outer surface in contact with the air, each casing being provided with a series of air pusher blades connected to and revolving with the casing and a series of stationary vanes in proximity to said air pusher blades, the air pusher blades of each casing delivering air to the associated stationary air vanes in said casing, the said stationary air vanes delivering air from one casing to the pusher blades of the adjacent casing, the outer connecting walls of the adjacent casings projecting inwardly toward the center axis of the casings to form a constricted passageway between the adjacent casings, the air in the blower at all times passing along the external revolving walls of the casings and being cooled throughout its entire course through the

blower, a portion of the heat due to the compression of the air in the blower being removed from said compressed air so that when the compressed air is released and expanded to its normal atmospheric volume it will be cooler than the air as it entered the blower and can be used to cool compartments.

7. A device of the kind described comprising a casing having a centrally located air admission opening at one end and a centrally located air discharge opening at the other end, said openings being smaller in cross sectional area than the cross sectional area of the casing at the points where they connect with the casing, means for alternately expanding and compressing the air as it passes through the casing comprising a series of pusher blades connected with the casing, and projecting laterally beyond the periphery of the admission and discharge openings, means for rotating the casing so as to rotate said blades, and a series of vanes in proximity to said pusher blades and projecting laterally beyond the periphery of the admission and discharge openings and to the outer ends of which the air is delivered from the pusher blades, the vanes held against rotation, the outer ends of the vanes projecting beyond the outer ends of the pusher blades so that air is received by said ends from said pusher blades while the air is moving in a generally radial direction, the air at all points of its flow moving in a forward direction, the air on the outside of the casing absorbing heat from the air in the casing, the movement of the casing moving the air which has absorbed the heat away from the casing and causing cooler air to be brought into contact with the casing, so that when the air passing through the casing is released and expanded to its normal atmospheric volume it will be cooler than the air as it enters the blower and can be used to cool compartments.

WILLARD LANGDON MORRISON.
